UNITED STATES PATENT OFFICE.

HANS FREDRIK HANSEN, OF GRANITE HEIGHTS, WISCONSIN.

ENVELOP-OPENER.

No. 889,004.

Specification of Letters Patent.

Patented May 26, 1908.

Application filed March 10, 1906. Serial No. 305,341.

To all whom it may concern:

Be it known that I, HANS FREDRIK HANSEN, a citizen of the United States, residing at Granite Heights, in the county of Marathon and State of Wisconsin, have invented a new and useful Improvement in an Envelop-Opener, of which the following is a specification.

This invention is an improved construction of envelop opener, the object being to provide a cheap and simple construction of device, by means of which the envelop can be quickly and easily opened and all danger of the blade slipping during said operation, entirely avoided.

Another object of the invention is to construct the device in such manner that it can be conveniently carried in the pocket when desired.

With these objects in view the invention consists in the details of construction herein-after fully described and pointed out in the claims.

In the drawings forming a part of this specification:—Figure 1 is a perspective view showing the device arranged for carrying in the pocket. Fig. 2 is a similar view showing the device arranged ready for use as an envelop opener. Fig. 3 is an edge view partly in section. Fig. 4 is a vertical sectional view, the blade being shown in elevation. Fig. 5 is an enlarged detail view of the end of the handle in which the blade is fitted. Fig. 6 is an enlarged detail perspective view of the blade and its shank.

In carrying out my invention I employ a blade A, which is formed integral with the shank B, and between the shank and blade is the shoulder C.

D indicates the hollow handle bifurcated at its forward end as shown at D', and fitting in said bifurcated end is the shank B, a rivet E securing said shank and bifurcated end, the laterally projecting shoulders C, overlapping and bearing against the side portion of the handle as indicated at C', in Fig. 4, and it will be noted that the extreme ends of the bifurcated portion project beyond the shank and its shoulder and form guiding fingers D², upon the opposite sides of the blade as most clearly shown in Fig. 3. The shoulder is beveled in opposite directions as shown at C² in order to facilitate the opening operation as no edge or corner is permitted to project which could catch in the envelop being opened.

F indicates a sheath which is adapted to fit over the blade and a portion of the handle when the device is not in use and which is fitted upon the opposite end of the handle when the device is to be used, said sheath serving to increase the length of the handle and thereby render the device more convenient for use, a corrugation or bead D³ being produced about midway the length of the handle and which serves as a stop to limit the movement of the sheath when inserted upon said handle from either direction.

The device can be conveniently carried in the pocket as the blade is protected by means of the sheath as shown in Fig. 1 and when it is desired to use the device as an opener it is only necessary to remove the sheath from one end of the handle and place it upon the opposite end and the device is ready for use.

In operation the blade is inserted beneath the flap of the envelop, wrapper of the paper or package and is then pushed along in the usual manner and the guiding fingers D² will engage the edge of the envelop and will prevent the blade going too far into the envelop and will also prevent the said blade slipping to one side or the other. The shoulder being beveled in opposite directions at the forward end, prevents said shoulder binding against the edge of the envelop or wrapper.

Having thus fully described my invention, what I claim as new and desire to secure by Letters Patent, is:—

An envelop opener comprising a hollow handle bifurcated at its forward end, a blade provided with a shank fitting in said bifurcation, laterally projecting shoulders formed on said shank adjacent said blade, overlapping and bearing against the side portion of said handle, the extreme end of the bifurcated portion projecting beyond the shoulders forming guide-fingers upon opposite sides of the blade, the shoulders being beveled in opposite directions forming guides, a corrugation formed on said handle, and a sheath adapted to fit over said handle, for the purpose set forth.

HANS FREDRIK HANSEN.
